RECEPTACLE FOR FOOD STUFFS

James D. Wilson, Long Beach, Calif., assignor to Banner Metals, Inc., Compton, Calif., a corporation of Ohio

Filed Nov. 12, 1965, Ser. No. 88,063

Term of patent 14 years

(Cl. D58—12.6)

FIGURE 1 is a perspective view of a receptacle showing my new design, taken from the front and to one side, the opposite side being a mirror image of the side shown in FIGURE 1;

I claim:

The ornamental design for a receptacle for food stuffs, substantially as shown and described.
